UNITED STATES PATENT OFFICE.

JOHN GEORGE LEYNER, OF DENVER, COLORADO.

COMBINED FRONT-CYLINDER-HEAD AND CROSS-HEAD SUPPORTING FRAME FOR STEAM AND POWER AIR-COMPRESSORS.

No. 797,519.

Specification of Letters Patent.

Patented Aug. 15, 1905.

Original application filed October 1, 1902, Serial No. 125,539. Divided and this application filed September 2, 1903. Serial No. 171,626.

To all whom it may concern:

Be it known that I, JOHN GEORGE LEYNER, a citizen of the United States of America, residing in the city and county of Denver and State of Colorado, have invented certain new and useful Improvements in a Combined Front-Cylinder-Head and Cross-Head Supporting Frame for Steam and Power Air-Compressors; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to improvements in air-compressors, and relates to a combined front-cylinder-head and cross-head supporting frame for steam and power air-compressors, and especially for compressors of the type described and set forth in an application filed by me on October 1, 1902, bearing Serial No. 125,539, and of which this present application is a divisional part.

The object of this invention is to provide a strong and rigid connection between the air-compressing cylinder and the operating steam-cylinder in steam-driven air-compressors or in power-driven air-compressors, such as belt or electric or water power driven air-compressors, which will interpose the required resistance in a direct line against the strain exerted between them.

A further object is to provide a connection of this character which is so constructed that one of its ends shall form the front cylinder-head for the adjacent end of the air-compressing cylinder, while its other end forms the head for the adjacent end of the operating steam-cylinder when steam is used as the motive power for the compressor, or is connected to the supporting-pedestal of the driving end of power-driven air-compressors, the said connection or long-distance piece also acting as a supporting-frame for the guideways of the cross-head of the piston-rod.

I attain these objects by the mechanism illustrated in the accompanying drawings, in which I have preferably illustrated my invention especially adapted to steam-driven air-compressors, and in which—

Figure 1 is a longitudinal sectional view through a portion of an air-compressing cyl-

inder and an operating steam-cylinder, showing the long-distance piece connecting the two cylinders. Fig. 2 is a longitudinal sectional view through the long-distance piece detached. Fig. 3 is a view looking from the under side thereof. Fig. 4 is a transverse sectional view thereof on the line 4-4 of Fig. 2. Fig. 5 is a transverse sectional view on the line 5-5 of Fig. 2, and Fig. 6 is a transverse sectional view on the line 6-6 of Fig. 2.

Referring to the accompanying drawings, the numeral 1 indicates an air-compressing cylinder, and 2 a bed-plate to which the cylinder is bolted. This cylinder is of the type illustrated and described in the application for a patent above referred to, and only a portion of it is here illustrated in order to clearly show the application of my present invention thereto. This cylinder is counterbored at its end, as shown at 3, and is surrounded by a water-jacket 4, at each end of which is an air-space 5 surrounding the cylinder, said air-spaces being connected by groups of air-pipes 6 and 7. Holes 8 connect the cylinder with the air-spaces, and these holes are normally closed by spring-actuated valves 9.

The numeral 10 refers to the cylinder of a suitable actuating steam-engine, only a fragment of which is illustrated, and the long-distance piece which constitutes my present invention connects these two cylinders, its ends being formed into suitable heads, which fit one upon the air-compressing cylinder and one upon the cylinder of the steam-engine. This distance-piece comprises an air-cylinder head 11 and a steam-cylinder head 12, and these heads are connected by suitable integral connecting-bars 13, which in cross-section are formed on the arc of a circle concentric with the axes of the cylinder-heads, which construction enables them to withstand greater longitudinal strain or pressure, and they are further strengthened by having their edges bent at an angle to form longitudinal ribs 14, which extend the entire length of the bars. Integral webs 15 are formed at the steam-cylinder end of the bars and extend about half the length of said bars, and these webs give additional rigidity to the bars. The distance-piece is thus constructed to withstand even a greater strain than is ever exerted upon it during the operation of compressing air. The air-cylinder head 11 is cast hollow in order to provide an air-space 16, and an an-

nular projection 17 is formed on its front face, which fits within the counterbore of the cylinder, and the head is secured to the cylinder by bolts 18, which pass through a circular series of holes 19 near the circumference of the head and into the wall of the water-jacket surrounding the cylinder.

An integral hub portion 20 is formed in the axial center of the air-space 16, which is bored to receive a suitable stuffing-box 21, and around this hub and concentric to its axis the walls of the head are provided with a plurality of holes 22, which are within the radius of the annular projection 17, and these holes are designed to receive suitable air-inlet valves 23, which form a communication between the air-space 16 and the interior of the air-compressing cylinder. Integral strengthening ribs and studs 24 and 25, respectively, extend from one wall of the head to the other and serve to brace the wall adjacent to the cylinder against the pressure exerted upon it by the compressed air in the cylinder. The air-space 16 is connected by openings 26 with an air-opening 27, formed in the bed-plate, which in turn connects with a conduit 28, formed in the foundation 29, and which opens into the atmosphere. The connecting-bars 13 extend from diametrically opposite points on the heads, and when the distance-piece is secured to the cylinders the bars are positioned one above the other. The steam-cylinder head 12 of the distance-piece is formed with an annular projection 30, which extends into the cylinder 10 of the operating steam-engine, and a bore 31 is formed in the axial center of this head, which is designed to receive a suitable stuffing-box 32. This head 12 is secured to the steam-cylinder by bolts which pass through holes 33 in the head and into the flange of the cylinder in the usual manner. At diametrically opposite points on the heads 11 and 12 and midway between the connecting-bars 13 are formed integral lugs 34 and 35, respectively, which project a suitable distance from the heads and are provided with vertical holes 36 and 37. The lugs on the same side of each head are in direct alinement with each other, and are provided a suitable distance from their ends with vertical shoulders 38 and 39, between which and the ends of the lugs the holes 36 and 37 are formed. To the oppositely-disposed lugs on each side of the head are secured a pair of guides 40 by bolts 41, which pass through holes in the ends of the guides and through the holes in the lugs, the ends of the guides abutting against the shoulders 38 and 39 on lugs. The guides support a cross-head 42, to which is threaded a two-part piston-rod 43, one end of which extends through the stuffing-box in head 11 and into the air-cylinder, where it is provided with a suitable piston, while the other end enters the steam-cylinder, as shown. The device herein described presents a strong

and compact connection between the air-compressing cylinder and the cylinder of the actuating-engine and is simple and cheap in construction.

Having fully described the invention, what I claim as new, and desire to secure by Letters Patent, is—

1. A device of the character described consisting of an integral casting comprising a pair of suitably-constructed and oppositely-arranged cylinder-heads which are connected by brace-bars, holes through said cylinder-heads in axial alinement with each other, and lugs upon opposite sides of each cylinder-head, and guideways connecting the lugs on one cylinder-head, with those on the other cylinder-head, substantially as shown.

2. A device of the character described, consisting of an integral casting comprising a pair of oppositely-arranged cylinder-heads, one of which is formed with an interior air-space, a bore in the axial center of each head, said bores being in axial alinement with each other, a circular series of holes through the head having the air-space which are concentric with its central bore, integral brace-bars which connect the two heads; and lugs on opposite sides of each head, and guideways which connect the lugs on one head with those on the opposite head, substantially as shown.

3. A device of the character described, consisting of an integral casting comprising a pair of oppositely-arranged cylinder-heads, which are connected by integral brace-bars, an air-space in one of said heads, an integral hub in said air-space in the axial center of said head, a bore through said hub, a circular series of holes through said head concentric with the bore and air-passages connecting said air-space with the atmosphere; a bore in the opposite head in axial alinement with the above-mentioned bore; and lugs on opposite sides of each cylinder-head and guideways connecting the lugs on one cylinder-head, with those on the opposite head, substantially as shown.

4. A device of the character described consisting of an integral casting comprising a pair of oppositely-arranged cylinder-heads, one of which is formed with an interior annular air-space surrounding a central hub portion; brace-bars connecting said heads, which in cross-section are formed on the arc of a circle concentric with the axis of the head, their edges being formed into depending longitudinal ribs; a bore through the hub of one head; a circular series of holes through the walls of said head concentric with its bores, and air-passages connecting said interior air-space with the atmosphere; a bore in the opposite head in axial alinement with the above-mentioned bore; and lugs on opposite sides of each head and guideways connecting the lugs on one head with those on the other head, substantially as shown.

5. The combination with an air-compressing

cylinder and the cylinder of an actuating-engine of a distance-piece connecting the two cylinders, consisting of an integral casting comprising oppositely - arranged cylinder - heads which are united by brace-bars, one of said heads being secured upon the air-compressing cylinder and having an interior annular air-space which connects with the interior of said cylinder and with the atmosphere, while the opposite head is secured upon the cylinder of the actuating-engine, a bore through the center of each head, said bores being in axial alinement with each other; and lugs on opposite sides of each head and guideways secured upon and connecting the lugs on one head with those upon the other head, substantially as shown.

6. The combination with an air-compressing cylinder and the cylinder of an actuating-engine of a distance-piece connecting the two cylinders consisting of an integral casting comprising a pair of oppositely - arranged heads which are united by suitable brace-bars, one of said heads being bolted to the steam-cylinder, while the other head is bolted to the air-compressing cylinder, said air-cylinder head being formed with an interior annular air-space which surrounds a central hub portion, and with air-passages connecting said air-space with the atmosphere; an axial bore through the steam-cylinder head, an axial bore through the hub portion of the air-cylinder head, said bores being in alinement, a circular series of holes through the walls of the air-cylinder head, concentric with its axial bore, suitable valves in said holes which control the communication between the annular air-space of the cylinder-head and the interior of the air-cylinder; lugs on opposite sides of each cylinder and guideways secured to and connecting the lugs on one cylinder with those on the other cylinder, substantially as shown.

7. The combination with an air-compressing cylinder, the cylinder of an actuating-engine, and a piston-rod common to both cylinders which is provided centrally with a cross-head, of a distance-piece connecting the two cylinders, consisting of an integral casting comprising a pair of oppositely-arranged heads which are united by brace-bars, one of said heads being bolted to the cylinder of the actuating-engine, while the other head is bolted to the air-compressing cylinder, said latter

head being formed with an interior annular air-space which communicates with the atmosphere, said air-space surrounding a central hub portion; a bore through said hub portion, a bore through the steam-cylinder head, said bores being in axial alinement, suitable stuffing-boxes in each bore through which the piston-rod passes; lugs on opposite sides of the heads, guideways extending from the lugs of one head to those of the other head in which the cross-head of the piston-rod travels; a circular series of holes through the walls of the air-cylinder head, concentric with its axial bore, and valves in said holes which control the communication between the air-space of said head and the interior of the air-compressing cylinder, substantially as shown.

8. In an air-compressor, the combination with the cylinder of the long-distance piece consisting of an integral casting comprising the front cylinder-head of said cylinder at one end, the flange end at its opposite end, the intermediate arms, the guideways secured to said long-distance piece, the cross-head slidably supported in said guideways, the piston-rod secured to said cross-head and connected to said cylinder's piston and the stuffing-box in said cylinder-head of said long-distance piece operatively arranged around said piston-rod, substantially as described.

9. In an air-compressor, the combination with the cylinder and the piston of the long-distance piece consisting of an integral casting comprising the front cylinder-head of said cylinder, and the oppositely-disposed arms extending from said cylinder-head to a flanged head portion at its opposite end and adapted to be connected to any suitable power mechanism, the guideways, the cross-head and the piston-rod operatively supported by said long-distance piece, the stuffing-box in said cylinder-head in communication with the atmosphere, and the circular row of air-inlet valves arranged and adapted to admit air from said air-compartments to said cylinder during said cylinder's rearward stroke, substantially as described.

In testimony whereof I affix my signature in presence of two witnesses.

JOHN GEORGE LEYNER.
